(57) **CLAIM**

The ornamental design for a static weapon mount with electric lock, as shown and described.

DESCRIPTION

FIG. 1 is a top perspective view of the static weapon mount with electric lock of the instant invention;

FIG. 2 is a top view thereof;

FIG. 3 is a bottom view thereof;

FIG. 4 is a left side view thereof;

FIG. 5 is a right side view thereof;

FIG. 6 is a front side view thereof;

FIG. 7 is a rear side view thereof; and,

FIG. 8 is a reduced scale front perspective view illustrating the static weapon mount with electric lock secured to the inner surface of a vehicle trunk lid.

The portions of drawings illustrated by broken lines are for illustrative purposes and form no part of the claimed design.
